(57) **CLAIM**

The ornamental design of a food jar, as shown and described.

DESCRIPTION

FIG. 1 is a perspective view from above of the food jar design;

FIG. 2 is a perspective view from below of the food jar design;

FIG. 3 is a back view of the food jar design;

FIG. 4 is a front view of the food jar design;

FIG. 5 is a right side elevation view of the food jar design, with the left side elevational being a mirror image of FIG. 5;

FIG. 6 is a top view of the food jar design; and,

FIG. 7 is a bottom view of the food jar design.

It is to be understood that parts shown in dotted lines form no part of my inventive food jar design.
